(57) **CLAIM**

We claim the ornamental design for an oral airway device, as shown and described.

DESCRIPTION

FIG. 1 is a top perspective view of an oral airway device. FIG. 2 is a bottom perspective view of the oral airway device depicted in FIG. 1.

FIG. 3 is a left side elevational view of the oral airway device depicted in FIG. 1.

FIG. 4 is a right side elevational view of the oral airway device depicted in FIG. 1.

FIG. 5 is a top plan view of the oral airway device depicted in FIG. 1.

FIG. 6 is a bottom plan view of the oral airway device depicted in FIG. 1.

FIG. 7 is a front elevational view of the oral airway device depicted in FIG. 1; and,

FIG. 8 is a rear elevational view of the oral airway device depicted in FIG. 1.

The broken lines in the drawings illustrate portions of the oral airway device that form no part of the claimed design.
